UNITED STATES PATENT OFFICE

127,320

DESIGN FOR A PRESSING DEVICE

John J. Getgey, Cincinnati, Ohio, assignor to
Munny Manufacturing Company, Cincinnati,
Ohio, a corporation of Ohio

Application January 22, 1941, Serial No. 98,275

Term of patent 3½ years

To all whom it may concern:

Be it known that I, John J. Getgey, a citizen of the United States, residing at Cincinnati, in the county of Hamilton and State of Ohio, have invented a new, original, and ornamental Design for a Pressing Device, of which the following is a specification, reference being had to the accompanying drawing, forming a part thereof.

Figure 1 is a perspective view of a pressing device embodying my new design.

Figure 2 is a side elevational view thereof.
Figure 3 is a front elevational view thereof.

The characteristic feature of the design for a pressing device resides in a handle having the configurations shown, in association with the pressing blades illustrated.

I claim:

The ornamental design for a pressing device, substantially as shown and described.

JOHN J. GETGEY.
